UNITED STATES PATENT OFFICE.

ALEXANDRE M. GREAN, OF NEW YORK, N. Y.

BELTING.

1,280,986.

Specification of Letters Patent.

Patented Oct. 8, 1918.

Application filed September 8, 1916. Serial No. 119,094.

To all whom it may concern:

Be it known that I, ALEXANDRE M. GREAN, a citizen of the United States, residing at New York, in the county of New York, and 5 State of New York, have invented certain new and useful Improvements in Belting, of which the following is a specification.

The present invention relates to belting for apparel, such as girdles, linings and 10 the like, and the object is to provide a structure that will permit the body of the belting to be formed of a single strip, and yet have both a longitudinal and a transverse curvature, so that it will properly fit the 15 form of the wearer without wrinkling.

One embodiment of the invention is illustrated in the accompanying drawings, wherein:

Figure 1 is a side elevation of a section of 20 the material, with the portions at one end separated in order to illustrate its construction,

Fig. 2 is a similar view of the opposite side, and

25 Fig. 3 is a detail sectional view on an enlarged scale and substantially on the line 3—3 of Fig. 1.

Fig. 4 is a cross sectional view to illustrate the transverse curvature.

30 Similar reference numerals designate corresponding parts in all the figures of the drawings.

In the embodiment illustrated, a strip 4 of suitable material is employed that may 35 be of any desired length and width. This material is provided at intervals with transverse plaits 5, said plaits being curved and tapering substantially to a point 6 at one margin of the strip, the opposite portion being also tapered, but to a less degree, forming 40 a fold 7 in the opposite margin.

Extending longitudinally along the strip 4, and located nearer the edge having the folds 7 than the edge having the point 6, 45 is a reinforcing tape 8 that is secured to the strip by a line of stitching 9 which passes through the plaits 5, and thus assist in securing the same against unfolding.

On the same side of the body or belting 50 strip 4 as the tape 8 are placed transverse bones 10 preferably located in casings 11 and disposed over the plaits 5, being secured to the strip 4 and to the plaits 5 by lines of stitching 12 that pass through the plaits, 55 and thus effectively retain the same.

The edges of the body or belting strip 4

are preferably bound with tape 13 folded thereover and secured in place by lines of stitching 14.

Because of the curved formation of the 60 plaits, the belting strip is caused to have a transverse curvature, and as the folds of said plaits are greater at one edge of the belting strip than at the other, it will be evident that the strip also has a longitudinal 65 edgewise curvature, as shown in Figs. 1 and 2. Consequently, the article is shaped to conform to the contour of the wearer. It will be evident that it may be made of any length desired, and sections cut therefrom 70 for individual use.

In the actual construction, the method of making the strip is to form the plaits successively, lay the reinforcing tape 8 along the strip, and stitch it over the plaits as 75 they are formed. The bones are afterward applied and secured in place by lines of stitching, and finally the binding strips are placed in position and sewed.

From the foregoing, it is thought that the 80 construction operation and many advantages of the herein described invention will be apparent to those skilled in the art without further description, and it will be understood that various changes in the size, shape, 85 proportion and minor details of construction may be resorted to without departing from the spirit or sacrificing any of the advantages of the invention.

Having thus fully described my invention, what I claim as new, and desire to secure by Letters Patent, is:—

1. As an article of manufacture, a strip 90 of belting material having transversely disposed plaits therein, and bones secured over 95 said plaits.

2. As an article of manufacture, a strip of belting material having plaits therein, bones extending along said plaits, and means securing the bones to the strip, said means 100 constituting retaining means for the plaits.

3. As an article of manufacture, a strip of belting material having plaits therein, bones extending along said plaits, and lines of stitching securing the bones to the strip 105 and passing through the plaits.

4. As an article of manufacture, a strip of belting material having plaits therein, a longitudinal reinforcing tape extending across the plaits, and means securing the 110 reinforcing tape to the strip and securing the plaits against unfolding.

5. As an article of manufacture, a strip of belting material having plaits therein, a longitudinal reinforcing tape extending across the plaits, bones extending substantially longitudinally of the plaits, and means 45 securing the reinforcing tape and bones to the strip and securing the plaits against unfolding.
6. As an article of manufacture, a strip of belting material having plaits therein, a longitudinal reinforcing tape extending across the plaits, bones extending substantially longitudinally of the plaits, stitching 50 securing the tape to the strip and extending through the plaits, and stitching securing the bones to the strip and also extending through the plaits.
7. As an article of manufacture, a strip of belting material having transversely tapered 55 plaits therein that are wider at one end than the other, producing belting that is provided with a longitudinal edgewise curvature.
8. As an article of manufacture, a strip of belting material having transverse plaits 60 therein that taper substantially to a point at one margin of the strip and taper to a less degree toward the other margin whereby the strip has a longitudinal edgewise curvature, and means for preventing the plaits unfolding.
9. As an article of manufacture, a strip of belting material having transversely tapered 65 plaits therein that are wider at one end than the other, producing belting that is provided with a longitudinal edgewise curvature, and a reinforcing strip secured longitudinally to the belting strip across the plaits and nearer one edge than the other.
- 40 10. As an article of manufacture, a strip of belting material having transverse plaits 70 therein that taper substantially to a point at one margin of the material and taper to a less degree toward the other margin whereby the strip has a longitudinal edgewise curvature, and a reinforcing strip secured longitudinally to the belting strip across the plaits and nearer to the latter edge.
11. As an article of manufacture, a strip of belting material having transversely tapered 75 plaits therein that are wider at one end than the other, producing belting that is provided with a longitudinal edgewise curvature, a reinforcing strip secured longitudinally to the belting strip across the plaits and nearer one edge than the other, and bones disposed transversely of the belting strip and longitudinally over the plaits.
12. As an article of manufacture, a strip of belting material having transverse curved 80 plaits therein that taper to a greater degree toward one edge than toward the other edge, a longitudinal tape fixed to the belting strip nearer the latter edge, bones secured transversely to the belting strip over the plaits, and binding strips secured over the edges of the belting strip and over the ends of the bones.
13. As an article of manufacture, a flexible strip of belting material formed from a single piece and having a transverse curvature, and a longitudinal edgewise curvature.
14. As an article of manufacture, a flexible strip of belting material formed of a single piece and having curved transversely 85 disposed permanent plaits that are broader at one end than the other, whereby said strip has a transverse curvature and a longitudinal edgewise curvature.

In testimony whereof I affix my signature 80
in the presence of two witnesses.

ALEXANDRE M. GREAN.
